Primary Examiner — Darlington Ly*Assistant Examiner* — Daniel J Domino(74) *Attorney, Agent, or Firm* — Banner & Witcoff, Ltd.(57) **CLAIM**

The ornamental design for a display screen with icon, as shown and described.

DESCRIPTION

The FIGURE is a front view of a display screen with icon showing our new design.

The outermost broken line showing of a display screen portion and the broken line showing of the letter "T" element of the icon are provided for the purposes of illustrating portions of the article and do not form part of the claimed design.
